Primary Examiner — John R Yeh(74) *Attorney, Agent, or Firm* — Leydig, Voit & Mayer, Ltd.(57) **CLAIM**

The ornamental design for a surface cleaning pad, as shown and described.

DESCRIPTION

FIG. 1 is a top plan view showing my design for a surface cleaning pad;

FIG. 2 is a bottom plan view thereof; and,

FIG. 3 is an enlarged view taken from the indication in FIG. 1.

The dot-dash lines depict portions and boundaries of the surface cleaning pad that form no part of the claimed design. The claimed design is flat and co-planar with the surface of the surface cleaning pad. The black bars shown in FIGS. 1 and. 3 represent color contrast.
